GRADE CROSSING GUARD

George C. Burnison, Portland, Oreg.

Application May 2, 1938, Serial No. 205,529

3 Claims. (Cl. 39—6)

My invention relates to improvements in grade crossings in which stops are placed in each lane of traffic and at either side of the crossing whether the same is an arterial highway crossing, a railway or street car crossing, or any crossing of whatever nature in which a hazard to motorists is created.

I provide pits in the highway and covers for the pits. I also provide barriers adjacent the pit that may be raised and lowered, as when desired to prevent traffic passing along the highway at the crossings.

The primary purpose and object of my invention is to provide a guard in the lane of traffic to thereby minimize grade crossing dangers.

A further object of my invention is to provide at each grade crossing and in each lane of traffic, and at each side of the grade crossing, mechanical means for lessening the grade crossing hazards.

Heretofore it has been the general custom in America to provide only incomplete protection to the motorist at the grade crossings or to provide a sign that indicates that a hazard is to be crossed or to provide a gate or an under or an over crossing. If the latter two are employed, great expense is created to thereby lessen the number of such crossings to be installed as protection to the motorists.

Through the use of my new and improved device adequate protection is provided without the necessity for the great expense that is involved in the making of over or under crossings. With the increase in traffic speeds and the density of motorized traffic my device gives protection to the motorist and to the railroad and arterial traffic user and at an expense that is within reach of the suppliers of the same.

With these and incidental objects in view, the invention consists of certain novel features of construction and combination of parts, the essential elements of which are set forth in the appended claims, and a preferred form of embodiment of which is hereinafter shown with reference to the drawing which accompanies and forms a part of this specification.

In the drawing:

Fig. I is a side view of a quick return traffic barrier shown in fragmentary sectional side view, and wherein the barrier is made effective by being raised above the surface of the highway to act as a stop for vehicles.

Fig. II is a side view of the mechanism illustrated in Fig. I modified for cyclical velocity characteristics different from those of Fig. I.

Like reference characters refer to like parts throughout the several views.

I have shown my device as being disposed within a pit or well 1 below the surface of the highway with the primary top members 2 and 3 being disposed in surface alignment 4 of the pavement or roadway over which any suitable vehicle as an automobile 5 is being operated. The pit 1 is placed in the roadway and in a lane of traffic of the highway. These pits are placed in each of the traffic lanes of the highway.

I place a prime mover such as an electric motor 6 within the pit and connect the same with any suitable electric control mechanism placed 15 on the track over which the train is operated to energize the electric motor through one cycle of the operation due to the passing of the train over the track in either direction of the grade crossing.

20 The prime mover is mounted upon a support 7 which is normally raised by a plurality of coil springs 8 that are placed below the platform 7 and held in place by any suitable fastening down bolts 9. A worm screw 10 is secured to the armature shaft 11 of the prime mover and the worm shaft is journaled with any suitable journal bearing 11A that is mounted upon the platform 7.

The worm 10 coacts with and drives a worm gear 12, and the worm gear 12 is mounted upon any suitable shaft 13 and is journaled within suitable bearings not here shown. An elliptical gear 14 is mounted upon the shaft 13. A second shaft 15 is spaced apart from the shaft 13 and the longitudinal center lines of the respective shafts 13 and 15 are parallel. The elliptical gear 14 coacts with and drives the elliptical gear 16, and the shaft 15, upon which the gear 16 is mounted. The gears 14 and 16 are like in diameter and the number of teeth disposed thereupon.

40 The coacting gear 17 is mounted upon the shaft 15 and the same coacts with and drives a gear 18. The gear 18 is mounted upon a shaft 19 and a crank 20 is mounted upon the shaft 19 or is formed integral therewith and a connecting rod 21 is actuated by the crank 20. The connecting rod 21 is secured to a wrist pin 28 that is journaled within suitable bearings within a barrier block 29.

45 The barrier block 29 on one end is journaled about a shaft 30 and in its raised position the abutting surface 31 of the barrier block is raised within the pavement and acts as a stop over which the wheel or wheels of motor ve-

hicles may not be driven when the block is in a raised position.

At each cycle of energization of the prime mover 6 the barrier block 29 is raised from surface alignment to create a barrier in the roadway and in the lane of traffic in which the same is disposed.

The surface 32 of the barrier block 29 is normally disposed in surface alignment with the plates 2 and 3 and with the road surface 4 and is only raised at the time a car or train is being operated over the railway track at the crossing. The barrier is then electrically energized during the time the train is within the control of the electric block for energizing the prime mover. At the completion of the cycle of operation, the barrier block 29 is in full retracted position.

In Fig. I the mechanism is shown in an intermediate position in the operating cycle. Gears 17 and 18 are preferably made of equal diameters although they may be of unequal diameters as shown. When gears 17 and 18 are of equal diameters, the elliptical gears 14 and 16 provide a quick-return characteristic. If, in Fig. I it is stated that the barrier 29 is in the rising part of a cycle of operation, it will be evident that gear 16 is rotating at a lower angular velocity than gear 14. After the barrier 29 has been raised to its highest position, further rotation of the mechanism occurs with the elliptical gears in such relative position that gear 16 rotates at a higher angular velocity than gear 14 while the barrier 29 is being retracted. This provides the desirable velocity characteristics inherent in a mechanism which elevates the barrier 29 at a relatively low velocity and drops it quickly in retraction thereof. This is advantageous in operation inasmuch as it is desirable for barrier 29 to be raised into position comparatively slowly to avoid prematurely placing an obstacle in the roadway, and it is desirable to drop the barrier as quickly as possible once the necessity of its presence in the roadway has passed.

In Fig. II a modified form of actuating gear combination is shown for raising and lowering a stop block 51. The stop block 51 is hinged at one end as illustrated at 52 and is actuated by an eccentric arm 53 that is actuated through a train of gears illustrated in dotted lines at 54, 55, 56 and 57 through a worm 58 that is driven by an electric prime mover 59.

The mechanism of Fig. II is differentiated from that of Fig. I by having the connecting rod 53 operating the barrier 51. For a quick rise and slower return, the direction of rotation of the prime mover need only be reversed. In Fig. II the operation of the barrier is always in a one to one ratio with the elliptical gearing whereas in Fig. I, the interposition of gears 17 and 18 between the elliptical gears and the barrier permits a ratio different from one to one if desired.

While the form of mechanism herein shown

and described is admirably adapted to fulfill the object primarily stated, it is to be understood that it is not intended to confine the invention to the embodiment herein shown and described, 5 as it is susceptible of embodiment in various forms all coming within the scope of the claims which follow.

What I claim is:

1. In a grade crossing guard, the combination 10 of a retractile barrier which can be raised as an obstruction in the way of vehicular traffic in a roadway, a prime mover for raising and lowering said barrier and gearing interposed between said prime mover and said barrier, said 15 gearing comprising a speed reduction gear, a pair of elliptical gears, and a connecting rod for lifting said barrier, the elliptical gearing rotating in a one to one ratio with the cycle of raising and lowering said barrier and angularly 20 placed relative to said connecting rod to cause said barrier to be raised at one speed and to be lowered at a different speed.

2. In a device of the class described, comprising 25 a pit, a cover for said pit, with said cover being normally in alignment with the highway surface, said pit having a prime mover disposed therein, said prime mover adapted for being energized from a remote control station, an armature shaft adapted for being rotated when the prime mover is energized, a worm connected to the armature shaft, a worm gear coaxing with the worm, said worm gear being mounted upon a shaft, a crank shaft, a train of gearing adapted for being driven by the worm wheel for driving the crank shaft, a plurality of elliptical gears 30 disposed in said train of gears, a crank arm secured to and journaled relative to the crank shaft, said cover being hingedly supported on its one end and adapted for being raised and lowered through the action of the crank arm at each cycle of energization of the prime mover.

3. In a device of the class described, comprising 35 a pit disposed within a highway, a cover for the pit, with said cover adapted for being raised above the surface of the highway and the top surface of the cover being in normal surface alignment with the surface alignment of the highway, with one of the ends of the cover being curved and adapted for being raised to place a hazard in the line of traffic of vehicles flowing 40 thereover, an electric prime mover disposed within the pit, said electric prime mover adapted for being energized from a remote control station, a worm shaft secured to the armature shaft of the electric prime mover, a crank shaft 45 disposed within the pit, a crank arm connecting the crank shaft with the cover, and a train of gearing disposed between the worm and the crank shaft adapted for rotating the crank shaft when the worm is rotated, and a plurality of elliptical 50 gears disposed within said gear train.

GEORGE C. BURNISON.
